12 Claims. (Cl. 229—15)

The present invention relates to improvements in a paperboard container for the shipment or storage of produce such as tomatoes, other vegetables, fruit, etc. This container is preferably fabricated of corrugated board stock. The invention particularly concerns an improved, one-piece divider or partition unit which sub- 20 divides the interior of such a container into a pair of equal-sized compartments.

It is an object of the invention to provide a produce shipping container which comprises an external casing and an internal one-piece divider, which divider is characterized by a longitudinally extending partition of inverted V-shape in section, by certain floor panels which are integrally hinged to the walls of the divider at their lower margin thereof, and by outer wall elements which are disposed in inclined relation to the walls of the casing when the divider is operatively positioned within the latter, the arrangement being such that the wall elements and V-shaped partition of the divider coact in a novel manner with one another and with the walls of the casing to lock and effectively brace the divider against lateral shift or sway.

A still further object of the invention is to provide an improved, one-piece divider for a container of the above sort, featuring an inverted V-shaped, longitudinally extending partition adapted to constitute a central ventilating duct along the outer casing of the container, this partition being aligned with certain holes in the walls of the casing when the divider is operatively positioned in the latter, the inclined wall elements of the divider also coacting with the walls of the casing to provide side ventilating ducts paralleling and transverse of the partition.

A still further object is to provide a divider in which the two upstanding panel sections of an inverted V-shaped partition have ventilating openings at their hinged connection to the floor panels of the divider, for the distribution of air from the central ventilating duct referred to above to the spaces on opposite sides of the divider.

Yet another object is to provide a divider unit of the sort described above in which the improved structural features mentioned above are arranged in a manner to facilitate manipulation of the divider in inserting the same into an outer casing and removing the same from the casing.

Another object of the invention is to provide a paperboard or corrugated board blank of improved outline from which the divider described above is fabricated.

The foregoing statements are indicative in a general way of the nature of the invention. Other and more specific objects will be apparent to those skilled in the art upon a full understanding of the construction and operation of the device.

A single embodiment of the invention is presented herein for purpose of illustration. It will be appreciated that the invention may be incorporated in other modified forms coming equally within the scope of the appended claims.

2

In the drawings:

Fig. 1 is a perspective view, partially broken away, illustrating the main body section of a produce shipping container in accordance with my invention;

Figs. 2 and 3 are, respectively, views in vertical section along line 2—2 and 3—3, respectively, further illustrating structural details and relationships of the divider and associated outer container unit; and

Fig. 4 is a top plan view of an improved corrugated board blank employed in fabricating the divider.

Referring to Figs. 1, 2 and 3 of the drawings, the reference numeral 10 generally indicates an outer rectangular casing or container body with which the improved separator or divider 11 of the invention is associated. Casing 10 may be of any conventional construction and will receive a cover or an outer shell or envelope, not shown, also of any suitable, known type. Ordinarily this casing will carry side and end flaps at the top margin or lip of its walls. These have been omitted from the illustrated article for the sake of simplicity.

A ventilating hole 12 is formed in each of the opposed end walls 13 of the casing adjacent the bottom thereof, and a pair of longitudinally spaced holes 14 are likewise formed in each of the side walls 15 in a corresponding zone. The purpose of these openings will be herein-after referred to.

Divider-unit 11, in its operative, erected and installed position in the casing 10, comprises a central, longitudinally extending partition-unit 16 of inverted V-shaped cross section, having a pair of like wall panels 17 integrally connected to one another by creases 17, along the apex of the divider. The interior of the divider partition is in longitudinal alignment with ventilating holes 12, the panels 17 straddling this area as illustrated in Fig. 2.

Floor panels 18 are integrally joined to the divider 16 along the bottom extremities of the respective section 17. As illustrated in Fig. 4, showing the divider blank, panels 18 are integrally hinged to the respective partition panels 17 by means of a plurality of longitudinally spaced, longitudinally aligned creases 19, the ends of which are connected by U-shaped slits 20. Thus, as shown in Fig. 3, a plurality of longitudinally spaced ventilating openings 21 are formed along the lower margin of the panels 17, adjacent their hinged joint to floor panels 18. These openings assist in the distribution of air from the duct-like interior of partition 16 to the two compartments or cells defined by the latter.

Lateral or side wall panels 22, which in operative position are inclined upwardly and outwardly relative to casing side walls 15 (Fig. 2), are integrally hinged to the outer margins of the respective floor panels 18 by means of a series of aligned creases 23 and connecting U-shaped slits 24 (Fig. 4). These are of the same character as the slits and creases 19, 20, described above. Side wall panels 22 of the blank have outwardly flaring or divergent end margins 25, for a purpose which will become evident.

The blank is completed by end wall panels 26 which in operative position are inclined upwardly and outwardly relative to casing end walls 13. These panels are integrally hinged by the spaced creases 27 and connecting U-shaped slits 28 to end margins of the respective floor panels 18. The inner end margins 29 of the two panels 26 at either end of the blank are mutually convergent, and the width of the panels 26 is increased somewhat at 30 to extend outwardly beyond the lines of the two side wall panel hinge creases 23. The outer side margins 31 of panels 26 parallel the respective lines of creases 23. The ends of the hingedly connected partition sections 17 are extended longitudinally beyond the line of the creases

27 which hinge divider end wall panels 26 to floor panels 18.

In assembling the divider 10 in the outer casing 11, the medial partition crease 17' is manually pre-broken downwardly and the various divider wall and floor panels 18, 22, 26 are also pre-broken in the opposite direction about their respective creases to one another and to the partition section 17. The panels 17 of partition 16 are then compressed sufficiently to increase clearance of the divider relative to the side walls 15 of the casing, whereupon the divider is dropped or pushed into the latter. Floor panels 18 are engaged with the bottom 32 of casing 11 and partition 16 is released, whereupon its inherent resilience causes the divider unit to expand outwardly into the operative position illustrated in Figs. 1, 2 and 3.

In this position of the divider its partition 16 and its various panels are very strongly and effectively braced by interengagement with one another. For example, end wall panels 26 have edge engagement at their respective inner, convergent edges 29 with the side surfaces of the partition panels 17, in substantially spaced relation inwardly of the longitudinally projected ends of the partition as illustrated in Fig. 3. Their outer edges 31 are directly butressed by casing side walls 15. At the same time, the inner surfaces of divider end panels 26 are edge-engaged by the outwardly divergent end edges 25 of the side wall panel 22 (Fig. 2). Thus any tendency of the partition 16 to sway or shift sidewardly is resisted by panels 26 and any tendency of these end wall panels 26 to shift endwise out of bracing position is effectively contained by the panels 22 and end walls 13. This is the case even should side wall panels 22 shift inwardly somewhat, though the contents of the container will ordinarily prevent this. The floor panels 18 cannot slide outwardly. A very strong and rigid divider construction which correspondingly strengthens and rigidifies the container as a whole, is thus provided.

The respective divider end and side wall panels 26, 22, in their inclined relationship to the end and side walls 13, 15 of casing 10, afford ventilating spaces along the sides and ends of the divider, and the spaces defined by side panels 22 are open to the ventilating holes 14. The entire interior of the casing 10 is well ventilated to eliminate spoilage of produce in transit, and uniformity of distribution of ventilation is furthered by the small ventilating openings 21 respective junctures of the partition, floor and wall panels 17, 18, 22 and 26 of the divider. It may be noted that spoilage of fruit and produce most frequently occurs adjacent the walls of any shipping container, particularly at the bottom zone thereof. Hence the provisions described are of particular value in correcting this drawback.

It will also be noted that ventilation is further improved by the fact that the respective pairs of flap-like members which constitute the bottom 32 of outer container 10 do not quite meet at the center of the latter. This affords a bottom air opening 33 (Figs. 2 and 3) for the supply and discharge of air.

I claim:

1. A one-piece divider unit for a shipping container or the like, comprising, in operative condition, a pair of like, upstanding rectangular sections integrally hinged to one another and constituting a longitudinally extending endwise partition, said sections being disposed in inverted V-shaped outline, floor panels integrally hinged to the lower margin of said respective sections and extending outwardly therefrom, and upstanding end wall panels integrally hinged to said floor panels at opposite ends thereof, the hinged connection of said floor and end wall panels being located inwardly of the ends of the partition sections, said end wall panels being disposed in outwardly inclined relation to the vertical and having acutely inclined inner edges in edge engagement with surfaces of said respective partition sections inwardly of the opposite ends thereof to brace said partition against lateral shift,

4
said end wall panels having parallel outer side edges at an acute angle to said inner edges.

2. A one-piece divider unit for a shipping container or the like, comprising, in operative condition, a pair of like, upstanding rectangular sections integrally hinged to one another and constituting a longitudinally extending endwise partition, said sections being disposed in inverted V-shaped outline, floor panels integrally hinged to the lower margin of said respective sections and extending outwardly therefrom, upstanding end wall panels integrally hinged to said floor panels at opposite ends thereof, the hinged connection of said floor and end wall panels being located inwardly of the ends of the partition sections, said end wall panels being disposed in outwardly inclined relation to the vertical and having acutely inclined edges in edge engagement with surfaces of said respective partition sections inwardly of the opposite ends thereof to brace said partition against lateral shift, and side wall panels integrally hinged to said respective floor panels along opposite sides thereof, said side wall panels having acutely inclined end edges in edge engagement with surfaces of said end wall panels inwardly of the outer edges of the latter to brace said end wall panels.

3. A shipping container including a divider unit comprising a pair of like, upstanding rectangular sections integrally hinged to one another and constituting a longitudinally extending endwise partition, said sections being disposed in inverted V-shaped outline, floor panels integrally hinged to the lower margin of said respective sections and extending outwardly therefrom, and upstanding end wall panels integrally hinged to said floor panels at opposite ends thereof, the hinged connection of said floor and end wall panels being located inwardly of the ends of the partition sections, said end wall panels being disposed in outwardly inclined relation to the vertical and having inclined margins in edge engagement with surfaces of said respective partition sections inwardly of the opposite ends thereof to brace said partition against lateral shift, and an outer casing for said unit having vertical walls engaged by said respective end wall panels adjacent the top of the latter, said end wall panels having parallel outer edges disposed at a right angle to the hinge between the floor and end wall panels and having edge engagement along their length with opposed vertical walls of said casing.

4. A shipping container including a divider unit comprising a pair of like, upstanding rectangular sections integrally hinged to one another and constituting a longitudinally extending endwise partition, said sections being disposed in inverted V-shaped outline, floor panels integrally hinged to the lower margin of said respective sections and extending outwardly therefrom, upstanding end wall panels integrally hinged to said floor panels at opposite ends thereof, the hinged connection of said floor and end wall panels being located inwardly of the ends of the partition sections, said end wall panels being disposed in outwardly inclined relation to the vertical and having inclined margins in edge engagement with surfaces of said respective partition sections inwardly of the opposite ends thereof, to brace said partition against lateral shift, and side wall panels integrally hinged to said respective floor panels along opposite sides thereof, said side wall panels having edge engagement with surfaces of said end wall panels inwardly of the outer edges of the latter to brace said end wall panels, and an outer casing for said unit having vertical end and side walls engaged by said respective end and side wall panels adjacent the top of the latter.

5. A one-piece blank for a container divider unit comprising a pair of like rectangular partition forming sections integrally hinged to one another, floor panels integrally hinged to opposite side margins of said sections, and end wall panels integrally hinged to said respective floor panels at opposite ends thereof, the hinged connection of said floor and end wall panels being located inwardly of the ends of the partition sections and extending at a right angle

to the latter, said end wall panels having adjacent, mutually facing, outwardly convergent inner side edges.

6. A one-piece blank for a container divider unit comprising a pair of like rectangular partition forming sections integrally hinged to one another, floor panels integrally hinged to opposite margins of said sections, and end wall panels integrally hinged to said respective floor panels at opposite ends thereof, the hinged connection of said floor and end wall panels being located inwardly of the ends of the partition sections and extending at a right angle to the latter, said end wall panels having adjacent, mutually facing, outwardly convergent inner edges and opposed outer side edges which project outwardly beyond the side margin of the floor panel and parallel the floor panel hinge.

7. A one-piece blank for a container divider unit comprising a pair of like rectangular partition forming sections integrally hinged to one another, floor panels integrally hinged to opposite side margins of said sections, end wall panels integrally hinged to said respective floor panels at opposite ends thereof, the hinged connection of said floor and end wall panels being located inwardly of the ends of the partition sections and extending at a right angle to the latter, said end wall panels having adjacent, mutually facing outwardly convergent inner side edges, and side wall panels integrally hinged to said floor panels along opposite sides thereof, said end wall panels having opposed outer side edges which project outwardly beyond and parallel the hinges between said floor and side wall panels.

8. A one-piece blank for a container divider unit comprising a pair of like rectangular partition forming sections integrally hinged to one another, floor panels integrally hinged to opposite side margins of said sections, end wall panels integrally hinged to said respective floor panels at opposite ends thereof, the hinged connection of said floor and end wall panels being located inwardly of the ends of the partition sections and extending at a right angle to the latter, said end wall panels having adjacent, mutually facing, outwardly convergent inner side edges and opposed outer edges which parallel the floor panel hinge, and side wall panels integrally hinged to said floor panels along opposite sides thereof, said end wall panels having opposed outer side edges which project outwardly beyond and parallel the hinges between said floor and side wall panels.

9. A one-piece blank for a container divider unit comprising a pair of like rectangular partition forming sections integrally hinged to one another, floor panels integrally hinged to opposite side margins of said sections, end wall panels integrally hinged to said respective floor panels at opposite ends thereof, the hinged connection of said floor and end wall panels being located inwardly of the ends of the partition sections and extending at a right angle to the latter, said end wall panels having adjacent, mutually facing, outwardly convergent inner side edges and opposed outer edges which parallel the floor panel hinge, and side wall panels integrally hinged to said floor panels along opposite sides thereof, said end wall panels having opposed outer side edges which project outwardly beyond

and parallel the hinges between said floor and side wall panels, said side wall panels having outwardly divergent end edges.

10. A one-piece blank for a container divider unit comprising a pair of rectangular partition forming sections integrally hinged to one another, floor panels integrally hinged to opposite margins of said sections, and end wall panels integrally hinged to said respective floor panels at opposite ends thereof, the hinged connections of said end wall panels and said floor panels being at right angles to the hinged connections of said floor panels and said partition forming sections and the ends of the partition forming sections extending outwardly thereof, said end wall panels having a width at the hinged connection with the floor panels which is greater than the width of the floor panels and having adjacent, mutually facing, outwardly convergent inner edges and opposed outer edges which parallel the floor panel hinge.

11. A one-piece blank for a container divider unit comprising a pair of rectangular partition forming sections integrally hinged to one another, floor panels integrally hinged to opposite margins of said sections, and end wall panels integrally hinged to said respective floor panels at opposite ends thereof, the hinged connections of said end wall panels and said floor panels being at right angles to the hinged connections of said floor panels and said partition forming sections and the ends of the partition forming sections extending outwardly thereof, said end wall panels having a width at the hinged connection with the floor panels which is greater than the width of the floor panels and having adjacent, mutually facing, outwardly convergent inner edges and opposed outer edges which parallel the floor panel hinge, and side wall panels integrally hinged to said floor panels along opposite sides thereof.

12. A one-piece blank for a container divider unit comprising a pair of like rectangular partition forming sections integrally hinged to one another, floor panels integrally hinged to opposite margins of said sections, and end wall panels integrally hinged to said respective floor panels at opposite ends thereof, said end wall panels having adjacent, mutually facing, outwardly convergent inner edges and opposed outer edges which parallel the floor panel hinge, and side wall panels integrally hinged to said floor panels along opposite sides thereof, said side wall panels having outwardly divergent end edges.
